18 Claims. (Cl. 315—12)

1

Our invention relates to cathode ray storage tube apparatus and particularly to methods of and means for utilizing such apparatus for ground clutter reduction in radar systems, for delaying signals, etc.

The invention will be described with particular reference to the use of a television pick-up tube of the type known as the Image Orthicon especially as applied to a radar system for distinguishing between stationary and moving objects. One of the difficulties in detecting aircraft approaching a radar station, particularly if the aircraft is at a low altitude, is that the signal reflected from the ground or from buildings or hills obscures the signal reflected from the aircraft. Such obscuring signals are referred to as ground clutter. Similarly, signal reflected from an aircraft flying through a region filled with floating metal foil or the like may be obscured by reflections from the metal foil.

One of the objects of the present invention is to provide an improved method of and means for distinguishing between signals reflected from stationary or substantially stationary objects and signals reflected from moving objects.

A further object of the invention is to provide an improved method of and means for reducing the amount of ground clutter or the like in a radar picture.

A still further object of the invention is to provide an improved method of and means for utilizing a cathode ray storage tube of the low-velocity-beam double-sided-mosaic type for distinguishing between signals reflected from stationary objects and signals reflected from moving objects.

A still further object of the invention is to provide an improved method of and means for utilizing a cathode ray storage tube of the low-velocity-beam double-sided-mosaic type for delaying signals.

A still further object of the invention is to provide an improved method of and means for indicating any difference in signals that occur in succession.

According to one preferred embodiment of the invention, a cathode ray storage tube of the Image Orthicon type is employed in combination with a pulse-echo radar system of the coherent pulse type. By utilizing a coherent pulse system the phase of the carrier wave of the reflected pulse may be compared with a carrier wave of fixed phase so that any change in phase due to motion of the reflecting object may be detected. Thus, there may be supplied to the

2

storage tube a received signal that remains the same for successive received pulses if the pulses are reflected from a stationary object but which is different for each received pulse if the reflecting object is moving. The storage tube is employed for comparing the successive signals and is so operated that there is signal output only if successive signals are unlike.

In this embodiment of the invention for distinguishing between stationary and moving objects, the successive signals from the radar receiver or mixer are applied to a storage tube electrode so that one signal puts a charge pattern on the storage plate or target as it is scanned by an electron beam. If the next successive signal (produced by the next reflected pulse) is the same there will be no output signal but if it is different there will be an output signal or pulse indicating reflection from a moving object. At the end of the second signal (and the second electron beam scan) light is flashed on the photocathode of the storage tube to bring the tube back to its initial operating condition.

The invention will be better understood from the following description taken in connection with the accompanying drawing in which

Figure 1 is a block and circuit diagram showing one embodiment of the invention as applied to a pulse-echo radar system of the coherent pulse type wherein the signals are impressed upon a mesh screen electrode of the storage tube,

Figure 1A is a view illustrating a modification of the circuit shown in Fig. 1 wherein the signals are impressed upon the cathode of the storage tube,

Figure 2 is a group of graphs that illustrate the operation of the apparatus of Fig. 1 when successive received signals are alike.

Figure 3 is a group of graphs that illustrate the operation of the apparatus of Fig. 1 when successive received signals are different as when reflected from a moving object,

Figure 4 is a block and circuit diagram of an embodiment of the invention wherein the received signal is applied to a control electrode of the storage tube to modulate the electron beam of the storage tube instead of being applied to a screen adjacent to the target plate as in Fig. 1 or to the cathode as in Fig. 1A,

Figure 5 is a group of graphs that illustrate the operation of the apparatus of Fig. 4,

Figure 6 is a group of graphs that illustrate the use of the invention for delaying a signal where the signal is applied to the screen adjacent to the target plate,

Figure 7 is a group of graphs that illustrate the use of the invention for delaying a signal when the signal is applied to the electron beam modulating electrode, and

Figures 8 and 9 are block and circuit diagrams illustrating apparatus for delaying a signal in the way illustrated in Figs. 6 and 7, respectively.

In the several figures similar parts and similar graphs are indicated by similar reference characters.

Referring to Fig. 1, the radar system includes a radio pulse transmitter which comprises an oscillator 10 acting as a source of radio frequency energy and a power amplifier 11 which is pulse modulated by means of periodically recurring pulses supplied from a pulse generator 12 through a suitable modulating circuit 13. As in the usual pulse-echo systems, the resulting radio pulses radiated from the transmitter antenna 16 are of short duration compared with the period between successive pulses.

Pulses reflected from an object are picked up by a receiving antenna 17 and supplied to a mixer 18 which may be the same as the first detector or converted tube of a superheterodyne receiver. However, the local oscillator signal supplied to the mixer 18 is obtained from the R.-F. source 10 and is of the same frequency as the carrier wave of the received signal.

The output signal of the mixer 18 depends upon the phase relation of the received carrier wave signal with respect to the R.-F. signal supplied from the source 10 to the mixer. This output signal is the same for successive received pulses of R.-F. signal so long as this phase relation is unchanged, as when the signal is reflected from stationary objects. However, if the reflecting object is moving, the said phase relation is continuously changing and the mixer output signal is different for each received pulse.

In order to detect a changing signal and separate it from any unchanging signal, a cathode ray storage tube 21 is employed. The specific storage tube shown is the well known Image Orthicon which comprises a double-sided mosaic or target plate 22 on which signal is stored, a mesh screen electrode 23 close to the target plate 22, and a photoelectric cathode 24 on the large end of the tube envelope. The tube 21 further comprises an electron gun at the other end of the tube envelope which comprises a cathode 26, a control electrode 27, and a first anode 28. A storage tube of the Image Orthicon type is described in application Serial No. 554,494, filed September 16, 1944 in the name of Paul K. Weimer, and which is now U. S. Patent 2,433,941, issued Jan. 6, 1948.

The storage tube 21 is also provided with a wall coating 29 that is held at a potential less than that of the anode 28 and is further provided with a ring electrode 31 that is at ground potential. An external focusing coil 32 is provided. Thus, a low velocity electron scanning beam is directed against the target plate 22. The electron beam may be aligned by an alignment coil 33. It is caused to scan the target plate 22 by means of a deflecting yoke 34 which is supplied with sawtooth current from a deflection circuit 36. If desired, spiral scanning may be employed instead of sawtooth scanning.

The particular tube 21 being described by way of example is of the same design as the Image Orthicon employed for television pickup and, therefore, includes ring electrodes 37 and 38 for imaging the electrons from the photo-

electric cathode 24 upon the target plate 22. This imaging of the electrons is caused by the electrostatic field resulting from the ring electrode arrangement 37, 38 and by the electromagnetic field of the focusing coil 32. Such imaging is not essential for the use of the storage tube 21 in the present invention as electrons from the cathode 24 are utilized only to bring the target plate 22 to the potential of the screen 23 periodically as explained hereinafter.

In operation, as the scanning beam moves across the target plate 22 the number of electrons in the return beam depends upon the potential of the target plate. If the scanning beam strikes a spot on target 22 that at maximum positive potential, there will be a minimum number of electrons in the return beam. The return beam releases secondary electrons from the end plate of the anode 28 and these electrons are directed, by means of a persuader ring electrode 39, into a three-stage electron multiplier 41, 42, 43. The electrons from the last stage strike a secondary electron emitting plate 44 and the resulting electrons go to a screen electrode 46 whereby the output signal may be taken off an output resistor 47.

The storage screen or target plate 22 need not be described in detail. However, it may be mentioned that a preferred target plate 22 is made of very thin glass, the glass being so thin that elemental areas of the glass hold a charge for the desired length of time. Such a target plate is described in application Serial No. 631,441, filed November 28, 1941 in the name of Albert Rose as a continuation of Serial No. 357,543, filed September 20, 1940, now abandoned.

Referring more particularly to the circuit connections for the system of Fig. 1, the signal from the mixer 18 is supplied through an amplifier 40, over a conductor 48 and through a blocking capacitor 49 to the screen electrode 23 of the storage tube 21. A steady bias voltage is applied to the electrode 23 through a resistor 51. Also, a square wave bias voltage 52 is applied from a square wave generator 53 through a coupling capacitor 50 to the electrode 23. The square wave generator 53 is synchronized with the modulating pulse generator 12. The deflection circuit 36 is likewise synchronized with the generator 12.

At the end of every second scan of the scanning beam a pulse of light is flashed upon the photoelectric cathode 24 whereby electrons from cathode 24 bring the target plate 22 to the potential of the screen electrode 23 because of the capacity between the plate 22 and the screen 23. The light pulse may be obtained from any suitable source 54 which is energized from an electrical pulse source 56. The pulse source 56 is operated in synchronism with the modulating pulse generator 12.

The output signal of the storage tube 21 is taken off the resistor 47 and supplied through a blocking capacitor 57 to an amplifier 58. The amplified signal is supplied from amplifier 58 to the vertical deflecting plates of a cathode ray oscilloscope 59.

The horizontal deflecting plates of the oscilloscope 59 have a sawtooth voltage wave applied to them from a deflecting circuit 61 to deflect the electron beam of the oscilloscope along a time axis in synchronism with the deflection of the scanning beam of the storage tube 21. Any signal applied to the vertical deflecting plates of the oscilloscope 59 appears on the phosphores-

cent screen (not shown) of the tube 59 unless a blanking voltage is being applied to the oscilloscope control grid 62.

In the system illustrated, the square wave generator 53 supplies a square wave blanking voltage to the oscilloscope grid 62 through an amplifier 63 with the wave of the correct polarity to block the electron beam of the tube 59 during the first scan, i. e., during the scan immediately following the pulse of light from source 54.

Figs. 2 and 3 illustrate the operation of the system shown in Fig. 1. Referring first to Fig. 2, the top graph represents the radio pulses radiated from the transmitter antenna 16 and (in dotted line) the said pulses received at the receiving antenna 17 after reflection from an object which, in the present instance, is assumed to be stationary. The graph 66 represents the sawtooth current that flows through the storage tube deflecting yoke 34 to produce the first scan and the second scan of the target plate 22 by the scanning beam.

The graph 67 represents the light pulses that are produced at the end of the second scan and before the start of the first scan so that the capacity elements of the target plate 22 are brought to a predetermined potential (1 volt in the present example) at the end of each cycle of operation.

The rectangular wave biasing voltage 52 of one volt peak-to-peak swings the mesh screen electrode 23 first one-half volt below its $1\frac{1}{2}$ volt fixed bias to one volt and then one-half volt above its fixed bias to two volts through the alternating-current connection 50. This shift in the potential of screen 23 will be seen by comparing the starting points of the graphs 71a and 72a.

The graph 68 represents the sawtooth voltage applied to the horizontal deflecting plates of the oscilloscope 59.

The graphs 71 and 72 represent the signals from the mixer 18 during the occurrence of the received reflected pulses. The signals 71 and 72 are also shown expanded in order to illustrate the operation of the storage tube more clearly.

The graphs 71a and 72a show how the potential of the screen 23 varies with the applied signal and bias. The graphs 71b and 72b show that the glass target plate 22 varies in potential the same as the screen 23, this being due to the close spacing of the target plate 22 and the screen 23. Since the potential of the gun cathode is fixed at ground, this target plate potential is also the voltage difference between the target plate and the cathode.

During the first scan, as the scanning beam moves along the target plate from capacity element to capacity element the said capacity elements are being varied in potential by the screen 23 as shown at 71b. The capacity elements that are the more positive at the time the scanning beam strikes them will receive the more electrons from the beam, its velocity being so low that the ratio of primary electrons to secondary electrons is greater than unity. As a result, at the end of the first scan the charges on said scanned elements are represented by the dotted line graph 73.

During the second scan, as the scanning beam again moves over said capacity elements the target plate is being varied in potential the same as before by the signal on the screen 23, this target plate variation being represented at 72b. It will be seen that as a result of the signals 71 and 72 being identical, the potential variations rep-

resented by graphs 72b and 73 are identical except that they are of opposite polarity. Therefore, the net potential variation in said capacity elements as the beam scans along them is a zero variation as represented by the horizontal line 74. Thus, there is no variation in the number of beam electrons deposited on the target plate and so as indicated at 76 there is no variation in the return beam. This means that the signal output at the output resistor 47 is zero and that no indication will be produced on the screen of the oscilloscope 59 by the signals reflected by the stationary object. Preferably, the output signal indicated at 77 that is produced during the first scan is prevented from appearing on the oscilloscope screen by blocking the oscilloscope scanning beam during the presence of the signal.

When a radio pulse is reflected from a moving object a signal will appear on the oscilloscope screen. The operation of the storage tube in this case is shown in Fig. 3. Here the signals supplied from the mixer 18 during the first and second scans are represented by the graphs 81 and 82, respectively. Since the reflected pulses producing these signals are from a moving object such as an aircraft, the two signals are unlike for reasons previously explained.

The potential of screen 23 is varied during the two scans as shown at 81a and 82a. The target plate is correspondingly varied in potential as shown at 81b and 82b. The potential left on the target plate at the end of the first scan is indicated at 83. The net instantaneous potentials on the capacity elements as they are scanned the second time is shown by the graph 84. The resulting output signal is indicated by the graph 86. As previously stated, the signal output produced during the first scan as indicated at 87 is prevented from appearing on the oscilloscope 40 by the blanking voltage from amplifier 63.

From the foregoing it will be seen that the system of Fig. 1 will produce an indication only when the reflection is from a moving object. More generally stated, the system distinguishes between successive like signals and successive unlike signals.

As shown in Fig. 1A, the signals from the mixer 18 may be applied to the cathode 26 of the storage tube 21 by way of a lead 91 and an input resistor 92 that is connected between the cathode and ground. Likewise, the square wave biasing voltage may be applied to the cathode 26 by way of a lead 93 and the lead 91. The operation is the same as when the voltage variation between cathode and target plate is obtained by applying signal to the mesh screen 23.

Fig. 4 shows an embodiment of the invention where, instead of varying the voltage difference between cathode and target plate, the number of electrons in the scanning beam is varied. This modulation of the beam is produced by applying the received signal to the control electrode 27.

In order to compare two signals that successively modulate the scanning beam, it is necessary to reverse the polarity of one signal. This may be done as shown in Fig. 4 by applying to the control electrode 27 signal from the mixer 18 alternately through the amplifier 40 and through a polarity reversing amplifier 102. A square wave voltage from generator 53 is supplied through a reversing amplifier 103 and over a lead 104 to the amplifiers 40 and 102 to block amplifier 102 during the first scan and to block amplifier 40 during the second scan. Thus, as shown in Fig. 5, the scanning beam current is

varied during the first scan as indicated by the graph 106.

During the second scan the signal passes through the reversing amplifier 102 and the scanning beam is modulated as shown by graph 107 of Fig. 5. In the example illustrated the first and second signals are unlike since it is assumed that the pulses are reflected from a moving object.

At the start of the cycle of operation the target plate 21 is at two volts potential as shown by the graph 108, this being the fixed bias on the mesh screen 23. During the first scan the number of electrons deposited on the successive capacity elements struck by the scanning beam is as represented by the graph 109. The resulting charge on said elements at the end of the first scan is shown by the graph 111; the greater the number of electrons deposited, the more negative the charge.

At the start of the second scan the beam current is increased by the square wave voltage supplied over a conductor 112 to the control electrode 27 so that signal variations in either direction may be detected. More specifically, the beam current is increased to a value at the start of the second scan such that there are always more than enough electrons to bring the target plate to cathode potential. As the beam scans the target elements (which are charged as shown at 111) it brings these elements to the cathode potential, i. e., to ground potential. Therefore, the number of electrons in the return beam (and thus the output signal) depends upon the number of electrons that have to be deposited to bring the target elements to cathode potential and also upon the number of electrons in the scanning beam.

The number of electrons deposited during the second scan to bring the target plate to cathode potential is shown by the graph 112. It will be apparent that where the elements of the target plate are most negative they take a minimum number of electrons to bring them to ground potential. If the scanning beam contains a reduced number of electrons when it strikes these most negative elements, the number of return electrons will increase less than they otherwise would or will not increase at all. In the example shown, the first part of the second signal is the same as the first part of the first signal so that the return beam indicated at 113 is unchanged at first. However, the second signal then changes as compared with the first signal and there is a difference between the number of electrons deposited (graph 112) and the number of electrons in the scanning beam (graph 107) which difference is not a constant value. This variation in return beam current, represented at 113, is the desired output signal which indicates pulse reflection from a moving object.

In the circuit of Fig. 4 the function of the light pulse at the end of every second scan is to bring the target plate up to the mesh screen potential of two volts.

From the foregoing description of Fig. 4, it will be apparent that there will be an output signal from the storage tube only if successive signals are unlike as in the case of the signals resulting from reflection of pulses from moving objects.

As shown by the graphs of Fig. 6 and the block and circuit diagram of Fig. 8, the storage tube 21 may be employed for delaying a signal. In Fig. 8 the signal to be delayed is supplied through an amplifier 116 and through a coupling capacitor 117 to the screen electrode 23. A square wave voltage from the generator 53 is supplied over a conductor 115 and through a reversing amplifier

118 to the amplifier 116 so that signal is applied to the storage tube screen 23 during the first scan of the target plate 22 but not during the second scan. Also, square wave voltage from the generator 53 is applied over conductors 115 and 118 to the output amplifier 58 so that it is blocked during the first scan but passes signal during the second scan.

In Fig. 6, the graph 121 represents the signal applied to screen electrode 23 during the first scan. The resulting target plate potential variation is shown by graph 122. The return beam or output signal, represented by graph 123, is not passed by the amplifier 58. During the second scan the potential of the screen 23 is held at a steady bias voltage as shown at 124. Due to the charges left on the target plate by the first scan, as shown at 126, the second scan produces the delayed output signal represented at 127.

Fig. 9 shows how the signal may be applied to the control grid 27 to obtain a delayed signal. Here, as in Fig. 8, the input amplifier 116 passes signal during the first scan but not during the second scan as indicated by the graphs 131 and 132 of Fig. 7. During the first scan the target plate 22 remains at the screen potential of two volts as shown by graph 133 and the number of electrons deposited during this scan is shown by graph 134. There is no output signal during the first scan but since there may be a certain amount of noise signal it may be desirable to block the output amplifier 58 during this period.

During the second scan the charges left on the target plate elements by the first scan, as shown at 136, cause a corresponding variation in the electrons deposited during the second scan as shown at 137. The resulting return beam or delay output signal is shown at 138.

We claim as our invention:

1. The method of operating a cathode ray storage tube of the type having a target plate comprising capacity storage elements which comprises varying the potential of said target plate with reference to a fixed potential by a first signal as an electron beam scans capacity elements of said target plate, varying the potential of said target plate with reference to a fixed potential by a second signal as said electron beam again scans said charged capacity elements whereby the return beam from said target plate is signal modulated to produce an output signal only if said two signals are unlike.

2. The method of operating a cathode ray storage tube of the type having a target plate comprising capacity storage elements which comprises storing a first signal on said target plate as an electron beam scans capacity elements of said target plate, varying the potential of said target plate with reference to a fixed potential by a second signal as said electron beam again scans said charged capacity elements whereby the return beam from said target plate is signal modulated to produce an output signal only if said two signals are unlike, said capacity elements of said target plate being returned to a predetermined potential before the cycle of operation is repeated.

3. In combination a cathode ray tube having a mosaic that functions to store signals applied thereto, means for directing a beam of electrons against said mosaic, means for varying the potential of said mosaic with respect to a fixed reference potential and in accordance with an applied signal whereby the charge acquired by a capacity element of said mosaic when it is

scanned by said beam is a function of said mosaic potential, means for causing said beam to scan said mosaic once while a signal is varying the potential of said mosaic for causing the capacity elements of the mosaic which are thus scanned to acquire charges in accordance with the potential variations of the mosaic with reference to said fixed potential, means for causing said beam to scan said once-scanned elements a second time while an applied signal is again varying the potential of said mosaic with reference to said fixed potential whereby if the two signals are alike the voltage difference between the fixed potential point and successive scanned capacity elements is constant during said second scanning so that there is no signal output.

4. In combination, a cathode ray tube having a mosaic that functions to store signals applied thereto, means for directing a beam of electrons against said mosaic, means for varying the potential of said mosaic with respect to a fixed reference potential and in accordance with an applied signal whereby the charge acquired by a capacity element of said mosaic when it is scanned by said beam is a function of said mosaic potential, means for causing said beam to scan said mosaic once while a signal is varying the potential of said mosaic for causing the capacity elements of the mosaic which are thus scanned to acquire charges in accordance with the potential variations of the mosaic with reference to said fixed potential, means for causing said beam to scan said once-scanned elements a second time while an applied signal is again varying the potential of said mosaic with reference to said fixed potential whereby a signal output is obtained from the return beam only if there is a difference in said two applied signals, said mosaic being brought to a predetermined potential before the next cycle of operation.

5. The method of operating a cathode ray storage tube having a target plate comprising capacity storage elements and having an electron gun which comprises causing a low velocity electron beam from said gun to scan capacity elements of said target plate a first time and a second time, causing said electron beam to charge said scanned capacity elements at least during the first scan in accordance with a signal applied to said storage tube whereby the return beam from said target plate is signal modulated during the second scan unless a signal like the first signal is applied to said tube during the second scan, returning the capacity elements of said target plate to a predetermined potential at the end of the second scan, and repeating the cycle of operation.

6. In combination, a cathode ray storage tube having a target plate comprising capacity storage elements and having an electron gun, means for causing a low velocity electron beam from said gun to scan capacity elements of said target plate a first time and a second time, means for causing said electron beam to charge said scanned capacity elements at least during the first scan in accordance with a signal applied to said storage tube whereby the return beam from said target plate is signal modulated during the second scan unless a signal like the first signal is applied to said tube during the second scan, and means for returning the capacity elements of said target plate to a predetermined potential at the end of the second scan and before the cycle of operation is repeated.

7. The invention according to claim 6 wherein said last means comprises a photoelectric cath-

ode positioned to release electrons toward said target plate, and further comprising means for flashing light upon said photoelectric cathode at the end of the second scan and before the cycle of operation is repeated whereby electrons fall upon said target plate to return it to said predetermined potential.

8. In combination, a cathode ray tube having a double-sided mosaic that functions to store signals applied thereto, means for directing a beam of low velocity electrons against said mosaic, a fine mesh screen positioned close to said mosaic in capacitive relation thereto whereby the charge acquired by a capacity element of said mosaic when it is scanned by said beam is a function of the potential of said mesh screen and of the number of electrons in said beam, means for causing said beam to scan said mosaic once and for simultaneously causing the capacity elements of the mosaic which are scanned thereby to acquire charges in accordance with the variations of a signal applied to said tube, means for causing said beam to scan said once-scanned elements a second time while a signal is again being applied to said tube whereby a signal output is obtained from the return beam only if there is a difference in said two applied signals, and means for bringing said mosaic to the bias potential of said mesh screen at the end of said second scan and before the next first scan begins.

9. In combination, a cathode ray tube having a double-sided mosaic that functions to store signals applied thereto, means including an electron gun for directing a beam of low velocity electrons against said mosaic, said electron gun including a cathode, a fine mesh screen positioned close to said mosaic in capacitive relation thereto whereby the charge acquired by a capacity element of said mosaic when it is scanned by said beam is a function of the potential difference of said mesh screen and said cathode and of the number of electrons in said beam, means for causing said beam to scan said mosaic once and for simultaneously varying the voltage difference between said mesh screen and cathode in accordance with a signal for causing the capacity elements of the mosaic which are scanned by said beam to acquire charges in accordance with the variations of said signal, means for causing said beam to scan said once-scanned elements a second time while a signal is again varying said voltage difference whereby a signal output is obtained from the return beam only if there is a difference in said two applied signals, and means for bringing said mosaic to the bias potential of said mesh screen at the end of said second scan and before the next first scan begins.

10. In combination, a cathode ray tube having a double-sided mosaic that functions to store signals applied thereto, means including an electron gun for directing a beam of low velocity electrons against said mosaic, said electron gun including a cathode, a fine mesh screen positioned close to said mosaic in capacitive relation thereto whereby the charge acquired by a capacity element of said mosaic when it is scanned by said beam is a function of the potential difference of said mesh screen and said cathode and of the number of electrons in said beam, means for causing said beam to scan said mosaic once and for simultaneously varying the voltage difference between said mesh screen and cathode in accordance with a signal for causing the capacity elements of the mosaic which are scanned by said beam to acquire charges in ac-

cordance with the variations of said signal, means for causing said beam to scan said once-scanned elements a second time while a signal is again varying said voltage difference whereby a signal output is obtained from the return beam only if there is a difference in said two applied signals, and means for bringing said mosaic to the bias potential of said mesh screen at the end of said second scan and before the next first scan begins, said last means comprising a photoelectric cathode and means for projecting a pulse of light thereupon between the end of the second scan and the beginning of the following first scan.

11. The method of operating a cathode ray storage tube having a target plate comprising capacity storage elements and having an electron gun that includes a cathode which comprises storing a first signal on said target plate as a low velocity electron beam from said gun scans capacity elements of said target plate, varying the voltage difference between said cathode and said target plate by a second signal as said electron beam again scans said capacity elements whereby the return beam from said target plate is signal modulated only if said two signals are unlike, returning the capacity elements of said target plate to a predetermined potential at the end of the second scan, and repeating the cycle of operation.

12. In combination, a cathode ray storage tube having a target plate comprising capacity storage elements and having an electron gun that includes a cathode, means for storing a first signal on said target plate as a low velocity electron beam from said gun scans capacity elements of said target plate, means for varying the voltage difference between said cathode and said target plate by a second signal as said electron beam again scans said capacity elements whereby the return beam from said target plate is signal modulated only if said two signals are unlike, and means for returning the capacity elements of said target plate to a predetermined potential at the end of the second scan and before the cycle of operation is repeated.

13. The method of operating a cathode ray storage tube of the low velocity beam type having a target plate comprising capacity storage elements which comprises storing a first signal on said target plate as a low velocity electron beam scans capacity elements of said target plate, varying the potential of said target plate by a second signal as said electron beam again scans said capacity elements whereby the return beam from said target plate is signal modulated only if said two signals are unlike, returning the capacity elements of said target plate to a predetermined potential at the end of the second scan, and repeating the cycle of operation.

14. In combination, a cathode ray tube having a double-sided mosaic that functions to store signals applied thereto, means for directing a beam of low velocity electrons against said mosaic, a fine mesh screen positioned close to said mosaic in capacitive relation thereto whereby the charge acquired by a capacity element of said mosaic when it is scanned by said beam is a function of the potential of said mesh screen and of the number of electrons in said beam, means for causing said beam to scan said mosaic once and for simultaneously causing the capacity elements of the mosaic which are scanned thereby to acquire charges in accordance with the variations of a signal applied to said mesh screen.

15. In combination, a cathode ray tube having a double-sided mosaic that functions to store signals applied thereto, means for directing a beam of low velocity electrons against said mosaic, a fine mesh screen positioned close to said mosaic in capacitive relation thereto whereby the charge acquired by a capacity element of said mosaic when it is scanned by said beam is a function of the potential of said mesh screen and of the number of electrons in said beam, means for causing said beam to scan said mosaic once and for simultaneously causing the capacity elements of the mosaic which are scanned thereby to acquire charges in accordance with the variations of a signal applied to said mesh screen.

16. In combination, a cathode ray tube having a double-sided mosaic that functions to store signals applied thereto, means including a beam intensity control electrode for directing a beam of low velocity electrons against said mosaic, a fine mesh screen positioned close to said mosaic in capacitive relation thereto whereby the charge acquired by a capacity element of said mosaic when it is scanned by said beam is a function of the potential of said mesh screen and of the number of electrons in said beam, means for causing said beam to scan said mosaic once and for simultaneously causing the capacity elements of the mosaic which are scanned thereby to acquire charges in accordance with the variations of a signal applied to said mesh screen.

17. The method of operating a cathode ray storage tube having a target plate comprising capacity storage elements and having an electron gun which comprises storing a signal on said target plate only while a low velocity electron beam from said gun scans capacity elements of said target plate during a first scan, again scanning said capacity elements whereby the return beam from said target plate is modulated in accordance with said stored signal to produce a delayed signal, returning the capacity elements of said tar-

get plate to a predetermined potential at the end of the second scan, and repeating the cycle of operation.

18. The method of operating a cathode ray storage tube having a target plate comprising capacity storage elements and having an electron gun which comprises storing a signal on said target plate only while a low velocity electron beam from said gun scans capacity elements of said target plate during a first scan, again scanning 10 said capacity elements whereby the return beam

from said target plate is modulated in accordance with said stored signal to produce a delayed signal, projecting electrons upon the capacity elements of said target plate to bring them to a predetermined potential at the end of the second scan, and repeating the cycle of operation.
